WHEEL COVER

Arthur F. Carlson, Los Angeles, Calif., assignor to Shore-Calnevar, Inc., Paramount, Calif., a corporation of California

Filed Aug. 8, 1960, Ser. No. 61,668

Term of patent 14 years

(Cl. D14—30)

FIG. 1 is a perspective view of a wheel cover showing my new design;

FIG. 2 is a front view of the wheel cover shown in FIG. 1;

FIG. 3 is a cross-section taken along the line 3—3 of FIG. 2; and

FIG. 4 is an enlarged fragmentary perspective view showing the chevron-like ornamentation in detail.

The fragmentary portion of the mounting ring shown in FIG. 3 is for illustrative purposes only.

I claim:

The ornamental design for a wheel cover, substantially as shown and described.
